UNITED STATES PATENT OFFICE.

GEORGE B. GAINES, OF MOUNT VERNON, ASSIGNOR TO HIMSELF AND JOHN E. LANDERS, OF INDIANAPOLIS, INDIANA, ONE-HALF TO EACH.

HOMINY-MILL.

SPECIFICATION forming part of Letters Patent No. 233,341, dated October 19, 1880.

Application filed May 28, 1880. (No model.)

To all whom it may concern

Be it known that I, GEORGE B. GAINES, of Mount Vernon, in the county of Posey and State of Indiana, have invented a new and useful Hominy-Mill, of which the following is a specification.

My invention relates to improvements in hominy-mills, in which a revolving steam-drying grain-feeder and a series of adjustable 10 double-edged hollow-ground beater-knives projecting through the rim of a revolving wheel operate in conjunction with a stationary cylinder; and the objects of my improvements are, first, to provide a stationary cylinder of large diameter with an inner revolving wheel, the rim of which forms the inner revolving wall of the stationary cylinder; second, to provide the rim of the inner revolving wheel with a series of perforations or holes 15 corresponding to the cross-section of the adjustable beater-knives, for the purpose of holding the beater-knives in position and of preventing their turning or twisting, and thus prevent flour and meal from passing through 20 between the beater-knives and edges of the holes; third, to afford facilities for the proper adjustment of the beater-knives independent of each other either to or from the inner circumference of the stationary cylinder; fourth, 25 to provide the stationary cylinder with a smaller stationary cylinder above having a revolving feeding device heated by steam, by means of which the grain is dried and the temperature increased to a uniform condition 30 before treatment, and the grain well stirred and mixed preparatory to being discharged 35 into the annular space between the stationary cylinder and the rim of the revolving wheel; fifth, to provide the stationary cylinder with 40 a delivery-opening, the door of which is opened and closed automatically for holding the grain in the cylinder while under treatment, and for discharging the hominy or meal when ready for delivery; sixth, to provide an automatic device for revolving the steam-heating feeding 45 device and causing the grain, when heated to a uniform degree of temperature, to be deposited in the beating-cylinder.

I attain these objects by the mechanism

illustrated in the accompanying drawings, in 50 which—

Figure 1 represents a side elevation of the entire machine, with a portion of the side of the stationary cylinder broken away to show the manner in which the beater-knives project 55 through the rim of the inner revolving wheel into the annular space between said revolving rim and the inner curved side of the stationary cylinder. Fig. 2 is a front elevation of the same with the upper part cut away at the line 60 *x y* of Fig. 1. Fig. 3 is a portion of the rim of the revolving wheel, showing the shape of the holes for receiving and holding the beater-knives. Fig. 4 is a side view of one of the beater-knives and its adjusting screws and 65 nuts; also, the mechanism for attaching it to an arm of the revolving wheel, said arm being partially in section to show the mode of adjusting the beater-knife on said arm; and Fig. 5 is an end view of the beater-knife. 70

Like letters refer to like parts throughout the several views.

A represents the outer shell of a large cylinder, having annular rim sides B' on each end of a cylinder. 75

The shell A is mounted upon suitable supports or legs A' A'', which are secured to the floor or foundation of the cylinder. On one of the quartering sides of the cylinder A, above the support A', is an opening, K, in which is 80 fitted the curved door K', said door being hinged to the shell A at k, and the lower end of the door K' is provided with a side projecting arm, e, the use of which will be hereinafter described. 85

The upper central portion of the shell A is provided with a slit or aperture, r', which may be straight across the cylinder or diagonal. Above this slit or aperture r' is secured a small cylinder-shell, L, also provided with a slit or 90 aperture, r, corresponding to the aperture r' in the shell A. In the cylinder L is fitted a revolving drum composed of the heads M M' and circular sides M'' M'', leaving a space between them. Through the center of this revolving drum is secured a steam-pipe, N, having a series of pegs, p, radiating therefrom, as shown in Figs. 1 and 2. The upper side of the 95

shell L is provided with an opening and a hopper, L', for introducing the grain into the steam-drum M M³, as will be hereinafter described.

5 The revolving wheel inside of the stationary cylinder A is composed of the rim C, which is perforated with a series of holes, G⁴, Fig. 3, for holding and retaining in position the beater-knives G. The spokes D of the wheel C are 10 wide and thin, and each spoke is provided with a long slot, D', to receive and hold the bolt d, for adjusting and securing the angular brackets E and beater-knives G to said spokes.

The outer ends of each spoke are secured to 15 the inner circumference of the rim C by bolts b through the flanges a, as shown in Fig. 1. The other end of each spoke D is secured to the hub F, and the hub F is mounted on the shaft H, which shaft may be the main shaft of 20 an engine, if desired. The shaft H is mounted in boxes J or standards H' H', or in any other suitable manner, so that the rim C will revolve in the center of the shell A of the stationary cylinder, and form a revolving inner wall to 25 the annular space B of the outer stationary cylindrical shell A.

The beater-knives are constructed of steel, twelve inches long and six inches wide, with a cross-section similar to that shown in Fig. 5. 30 The longitudinal center of the knives is thick, as at G, and the blade is hollow-ground at each side of the center line, G, forming sharp edges, as shown at G' G², Figs. 4 and 5. At the rear end of each knife G is secured a screw-threaded shank, I, which is provided with two nuts, f f.

The shank I is inserted in a hole formed in the upright angular part of the angular bracket E, and made fast by the nuts f f, one on each side of the bracket E, as shown. The brackets 40 E are also adjustable on the spokes D by means of the slots D' and bolts d, by means of which the angular brackets, with their beater-knives, can be drawn toward the hub F and the knives withdrawn from the holes G⁴ in the rim C, or moved away from the hub and the knives inserted in the holes C⁴ of the rim C, and adjusted in close proximity to the inner wall of the stationary shell A.

The fine adjustments of each knife G may be 50 made by the screw I and nuts f f, or the blade of the knife G may be reversed thereby before being inserted in the holes G⁴ of the rim C. The reversing of the knives G and their adjustment lengthwise is frequently required, as the 55 edges wear off or the end of the blade becomes worn.

On the shaft H is secured a miter-wheel, g, which meshes in gear with a corresponding miter-wheel, g', mounted on the shaft P. The 60 shaft P is also mounted in suitable bearings on the post or other support Q, and is provided with a cone-pulley, O', as shown. Thus the cone-pulley O' has the same number of revolutions as that of the shaft H. Above or 65 at one side of the cone-pulley O' is another cone-pulley, O, mounted on another shaft, O²,

parallel with the shaft P, and supported in suitable bearings, the two cone-pulleys being reversed and motion communicated from one to the other by a belt (not shown) for the 70 purpose of increasing or diminishing the speed of the cone O'.

On one end of the shaft O² is secured a bevel-wheel, 10, which works in gear with a larger bevel-wheel, 9, mounted on the perpendicular shaft P', by means of which the shaft P' is rotated. The lower end of the shaft P' operates in a step-box or bearing, h², and is provided with a small bevel-wheel, 1, which works in gear with a larger bevel-wheel, 2, mounted 80 on one end of the horizontal shaft P³, said shaft being mounted in suitable bearing-boxes, h h'. The other end of the shaft P³ is provided with a bevel-wheel, 4, which works in gear with the small bevel-wheel 3, which is also 85 mounted on a stud or shaft supported in suitable bearings. On the back of the small wheel 3 is secured an arm, m, which radiates from the center of the wheel, and extends several inches beyond its periphery. This arm as it 90 is revolved by the gearing comes in contact with the side projecting arm e at the bottom of the door K', and forces said door open, and holds it in that position until the end of the arm m slips past the arm e, when the door K' is closed by the cord n and weight n', the cord 95 n operating over a pulley, 5, as shown. The door K' remains closed until the arm m again comes in contact with the arm e, when the operation of opening and closing the door K' is 100 repeated. The shaft P' is supported in suitable bearings, Q' Q², and the upper end of said shaft is also provided with a small bevel-wheel, 8, which works in gear with the bevel-wheel 7 on the horizontal shaft P². At the 105 end of the shaft P² nearest the cylinder L is another small bevel-wheel, 6', (shown in dotted lines in Fig. 2,) which works in gear with the bevel-wheel 6 on the steam-pipe N, by means of which the drum M M³ M' M² is 110 revolved in the shell L. The drum M M³ may fit snugly in said shell L and revolve therein, or the steam-pipe N may be mounted and revolved in removable boxes or glands s s', attached to the ends of the cylindrical shell L, 115 so as to revolve the drum, or the steam-pipe N may be stationary and the drum made to revolve on it by attaching the bevel-wheel 6 to one head, as at M, instead of to the pipe, the object being to heat the grain in the drum 120 to a uniform temperature, at the same time stirring it up by revolving the drum, aided by the pins p in the pipe N, before the grain is discharged through the openings r r' into the annular space B of the stationary cylinder A. 125

Having thus described the construction and arrangement of parts, I will now describe the mode of operation of my improved hominy-mill as follows, to wit:

The knives G being adjusted to project 130 across the annular space B of the shell A, and nearly touch the inner circumference of said

shell, the wheel C is set in motion, the outer periphery of the rim C forming the moving wall to the annular space B, and the knives G are revolved at one hundred or more revolutions per minute in said annular space. Several sets of these beater-knives G are arranged side by side, while others are arranged between them, as indicated in Fig. 3. The grain is then fed into the drum M, and hot steam circulated through the pipe N in said drum.

The gearing on the main shaft H and shaft P travels, by means of the cone-pulleys O O' and belt, (not shown,) to the shaft O², and by the gearing 10 9 to shaft P', and by gearing 8 15 and 7 to shaft P², and by gearing 6 6' to the steam-pipe N or drum M, thus causing the drum to revolve slowly and stirring the grain therein while the heated steam is raising the temperature of the corn to a uniform degree 20 before treatment. The corn, when thus heated, is deposited in the annular space B of the stationary cylinder through the holes r r', after which the drum M closes the discharge-openings r r', and is again filled with corn to be 25 heated, while the corn in the annular space B is being cut and bruised by being struck with the revolving knives G and knocked from side to side until converted into the desired grade of hominy.

30 Just before a new charge is introduced into the annular chamber B the arm m of the wheel 3 strikes the arm e on the door and opens it, thus permitting the hominy to be discharged. As soon as the hominy is removed 35 through the aperture K the door K' is closed by the weight n and cord n', and the drum arrives at a point to open the ports r r' and permit the freshly-heated charge to be deposited therein for a similar treatment.

40 It will be observed that the wheel 3 has a very slow motion, also the drum M, thus permitting the grain in the drum to have plenty of time to become heated to a uniform temperature; also, to permit the grain to remain 45 in the annular chamber B under action of the beater-knives sufficiently long to crack the corn into good hominy. The length of time required for each of these operations is regulated by the speed given by the wheels 3 and 6, and their 50 speed is regulated by the cone-pulleys O O'.

Having thus described my improvements and their mode of operation, what I claim is—

1. In a hominy-mill, the cylinder L, hopper L', and discharge-opening r, combined with 55 the revolving steam-heated drum M M' M² M³, the steam-pipe N, and pegs p, as and for the purpose specified.

2. In a hominy-mill, the combination of the stationary cylinder A, the revolving rim-wheel C, with beater-knives G, the cylinder L, and the 60 revolving steam-heated feed-drum M M' M² M³, substantially as and for the purpose specified.

3. In a hominy-mill, the outer stationary cylinder, A, having annular rim sides B', and its periphery, near the bottom, provided with 65 an opening, K, and curved door K', and the upper central part provided with a slit or aperture, r', combined with the revolving rim-wheel C, the rim of which fits and moves snugly between the annular sides B', and is 70 provided with a series of holes, G⁴, to receive and hold the beater-knives G, substantially as shown and described.

4. In a hominy-mill, the outer stationary cylinder, A, having annular rim sides B', and 75 its periphery near the bottom, provided with an aperture or opening, K, in which operates the curved door K', which is provided with a side projecting arm, e, a rope, n, and weight n', for closing it, combined with the wheel 3, having a radial arm, m, which opens the door K' as the wheel 3 revolves, all substantially as shown and described.

5. In a hominy-mill, the revolving rim-wheel C, having a series of diamond-shaped perforations, G⁴, in its rim, and thin flat spokes D, each spoke being provided with an oblong slot, D', combined with the adjustable angular brackets E and adjustable double-edged beater-knives G, all constructed and arranged 85 to operate in the manner substantially as shown and described.

6. In a hominy-mill, the double-edged hollow-ground beater-knife G, having the screw-threaded shank or stud I at one end, provided 95 with nuts f f', combined with the adjustable angular bracket E, and the slotted spokes D, all constructed and arranged to operate in the manner substantially as shown and described.

7. In a hominy-mill, the annular space B, 100 between the rim of the wheel C and inner wall of the shell A, and sides B', said annular space being of a uniform depth and width, and the joint between the stationary sides B' and edge of the revolving wheel made snug to prevent 105 leakage, combined with the beater-knives G or the revolving rim-wheel C, as and for the purpose specified.

In testimony whereof I have signed my name to this specification in the presence of two subscribing witnesses. 110

Witnesses: GEO. B. GAINES.

A. J. CLARK,
JAS. W. FRENCH.

Correction of Letters Patent No. 233,341.

It is hereby certified that in Letters Patent No. 233,341, issued October 19, 1880, upon the application of George B. Gaines, for an improvement in "Hominy Mills," the name of the assignee of one-half interest therein wherever it appears in said Letters Patent, and at the head of the printed specification forming a part thereof, was erroneously written and printed John E. Landers instead of John E. Sanders; that the correct name of said assignee is John E. Sanders; that the proper corrections have been made in the files and papers pertaining to the case in the Patent Office, and are hereby made in said Letters Patent to make the title therein conform to the records of the Patent Office.

Signed, countersigned, and sealed this 14th day of June, A. D. 1881.

[SEAL.]

A. BELL,
Acting Secretary of the Interior.

Countersigned:

E. M. MARBLE,
Commissioner of Patents.
